AUTOGRAPHIC REGISTER

Harry J. Waechter, Mount Healthy, Ohio, assignor to Paul Benninghofen and Fritz G. Diesbach, Hamilton, Ohio, as trustees

Application February 20, 1941, Serial No. 379,850

7 Claims. (Cl. 282—16)

This invention relates to manifolding or continuous form stationery of the type utilized in autographic registers and to the mechanism of these registers for feeding, aligning, and delivering the forms. More particularly, this invention is directed to improvements in manifolding stationery which comprises a plurality of superimposed forms of the type utilized in autographic registers, and to the cooperating feed mechanisms of these registers; whereby various lengths of forms, within practical limits, may be fed and positively aligned during the feeding operation without changing the feeding mechanism to suit the various lengths of forms. In other words, by utilizing the present invention, one standard feed mechanism is provided to feed and maintain in positive registry, forms of different lengths.

Thus, it has been an object of the present inventor to provide an autographic register and manifolding stationery for this register whereby accurate and positive alignment of the forms is made during every feeding operation and to provide the register with a set of compensating feed rolls for cooperation with corresponding apertures in the superimposed forms so that the one mechanism can be employed to feed, align, and dispense forms of widely varying lengths.

The present inventor has provided an autographic register which utilizes cooperating sets of discs or rolls, upper and lower, to feed and align the improved forms by virtue of their feeding relationship to apertures in the forms. The rolls are manually operated by a crank which is fixed to one end of the shaft carrying the lower set of rolls. The upper rolls are in positive transmission connection with the lower rolls by gears, and are carried on a common shaft which is spring urged to provide a peripheral contact between the two sets.

One embodiment of the invention may incorporate three sets of rolls, one engaging the strips midway of their widths, and the others engaging close to the respective margins of the strips. The lower rolls of the outer sets of rolls are provided with tread portions terminating at the proper point for freeing the strips from contacting pressure so that feed through these rolls is discontinued at the appropriate point. At this point, the center roll continues the feed until the forms, regardless of their lengths within practical limits, are substantially delivered; whereupon, the tread surface of the center roll or disc engages the upper roll through the enlarged apertures in the paper, and the feed is definitely stopped insofar as the center rolls are concerned. Thereupon,

pins associated with the outer rolls move into engagement with the apertures and feed and align the strips in the final short feeding phase.

The center holes in the paper are of sufficient size to permit lag of the marginal apertures relative to the line of contact of the outer rolls, so that the apertures can be entered by the pins without tearing the paper. The clearance afforded by the large central apertures permits the last feeding phase without any interference from the central rolls. These central rolls continue to engage through the aperture without placing any drag on the strips.

The strips, making up the successive packs of sales forms, include weakened tear-off lines defining the sales forms or slips. Each form includes three apertures which cooperate with the three sets of rolls. The central aperture, as stated, is larger than the marginal apertures, for the purpose of permitting the previously described lag of the marginal apertures and the final aligning feed of the paper without interference from the central set of rolls. These apertures have their centers in transverse alignment. The side apertures may be spaced any desired distance from the side edges; that is, they need not be as near the sides as shown.

The superimposed strips are fed through the rolls in three stages; one, a major feeding operation, in which all three sets of rolls advance the strips; two, an adjusting feeding operation in which the compensating rolls are employed to feed the strips; and three, a minor feeding operation wherein the strips are absolutely aligned and the forms dispensed.

In the first stage, the strips are always advanced a distance slightly less than the shortest form to be used. In this stage all three of the lower feed rolls engage the strips.

In the second stage, feeding of the strips by means of the two marginal feed rolls is discontinued as engagement by the tread portions ceases. Thereupon, the compensating feed roll alone is effective. The compensating feed roll advances the strips until the central apertures in the superimposed forms are all aligned between the compensating rolls. At this time, the feeding contact of the compensating rolls with the strips is broken since the rolls contact each other through the central apertures. Thus, it will be obvious that within practical limits, any length of form may be dispensed.

In the third stage or phase of feed, which is referred to as the aligning phase, the pins associated with the outer feed rolls become effective

by engagement within the lagging marginal apertures. At this time, of course, the outer feed rolls are out of engagement with the strips and the pins may move in easily and advance the strips by engagement with the forward walls of the marginal apertures. At this time, the strips slip forwardly between the central rolls within the clearance afforded by the large apertures.

The manifold pack or continuous form stationery disclosed in this application is disclosed and claimed in a copending divisional application filed Dec. 30, 1942, and bearing Serial No. 470,602.

Other objects and certain advantages of the present invention will be more fully apparent from a description of the accompanying drawings, in which:

Figure 1 is a perspective view of an autographic register embodying the present invention.

Figure 2 is a perspective view similar to Figure 1, in which the cover has been lifted back to expose the feeding mechanism and the writing platen, the stationery having been removed.

Figure 3 is a longitudinal sectional view taken on line 3—3, Figure 1.

Figure 4 is a sectional view taken on line 4—4, Figure 3, illustrating the feed rolls.

Figure 5 is a plan view of one of the forms showing the relative positions of the apertures.

Figure 6 is a sectional view taken on line 6—6, Figure 4, illustrating the center compensating rolls in position advancing the paper.

Figure 7 is a sectional view taken on line 7—7, Figure 4, illustrating an outer feed roll in the same relative position as the compensating rolls and near the conclusion of their strip advancing movement.

Figure 8 is a sectional view taken similar to Figure 6, but showing the compensating rolls in position where they register with the central apertures and are in the idling or adjusting portion of their rotation.

Figure 9 is a sectional view taken similar to Figure 7, but showing the outer feed rolls in the same relative position as the compensating rolls are shown in Figure 8 for illustrating the feeding pins about to come into engagement within the apertures for the final advance and adjustment phase of strip movement.

The continuous strips of forms illustrated here and forming a part of the present invention consist of lengths of paper providing forms 11 defined by weakened transverse tear lines 12. A large aperture 13 is provided centrally for each form midway of the width of the strip and at the head end of each form just back of the tear line. This aperture cooperates with the compensating rolls. Just back of the lines 12 in each case are the apertures 14, one adjacent each side of the strip and in alignment with the central aperture, crosswise of the strip. These apertures 14 cooperate with the outer feed rolls as will be described later in the specification.

Referring to the drawings, 15 indicates the casing of an autographic register providing an interior compartment 16 for a supply of zig-zag folded manifold forms 17 and a storage compartment 18 for receiving in refolded condition one of the strips for record purposes. This latter compartment, however, may be omitted where all strips of the pack are to be delivered from the machine. The strips are fed over a writing table or platen 19 which is disposed within the casing above the supply compartment. The platen 19 is hinged as at 20 at its rear edge to the side walls of the casing and is adapted to be swung up-

wardly for access to the compartment 16. The platen rests on a lip 21 turned inwardly from the wall of the casing on one side, and on the top edge of an internal wall 22 on the other side.

The feeding or translating rolls are operated by a crank handle 23 pinned to one end of a shaft 24 which carries the lower rolls. The crank is limited normally to a single continuous cycle of operation by a pair of spring-urged push pins extending from the side wall of the casing to interlock with the crank handle. Only one of these pins is shown at 25. When the handle is locked against rotation, the push pin, as a stop or limit against further rotation of the handle, is exposed and is accessible to the operator. By depressing the pin, the handle is released for a successive or subsequent cycle of operation. This type of stop or its equivalent is well known in the art and further illustration and description is believed unnecessary.

The strip feeding mechanism includes a set of upper rolls comprising an upper feeding or translating roll 26 at each side, and the long, upper compensating or adjusting feed roll 27 disposed between the rolls 26, 26. The upper rolls are carried on a common shaft 28 which is journalled in vertical slots 29 in an elongated journal box 30. The shaft is urged downwardly by means of coil springs 31—31 seated under compression in the journal box above the vertical slots. A pair of seats 32—32 provides for exertion of the spring pressure on the shaft. The journal box is fixed upon a cross section of a frame 33 which covers the top of the machine in a slightly elevated position from the writing table. The frame is provided with an opening for exposing a form section of the strip upon the platen and is hinged at its forward end to the casing so that it can be swung upwardly for access to the writing table for loading the machine.

The lower rolls are substantially larger than the upper rolls and include a pair of feeding rolls 34—34 and an adjusting or compensating feed roll 35. The shafts upon which the upper and lower rolls are carried are in positive transmission connection through meshing pinions 36 and 37 respectively. Each roll 34 carries a pin 38 extending radially slightly beyond the line of the periphery of the roll. The pins may be made integrally with the feed rolls, as shown, and are positioned on the inside of the roll in each case. The compensating feed roll 35 is mounted on the shaft 24 medially, between the two feed rolls.

The adjusting or compensating feed roll 35 has a continuous tread; that is to say, at no point is it relieved. Thus, it is continuously effective for feeding the paper until it has fed the strips to bring the central apertures in registry between it and its upper roll as illustrated in Figure 8. The outer feed rolls 34 provide tread portions 40 extending around approximately two-thirds of their circumferences. The balance of the outer surface of the outer feed rolls is relieved as at 41. These cutaway or relieved portions 41 are provided in order to release the feeding pressure on the forms so that the compensating rolls can bring the forms into registry in the second or compensating phase of strip feed. Pins 38—38 on the respective feed rolls project radially slightly beyond the tread portions and just ahead of them. Thus, the pins will engage with the side apertures just prior to the time that the tread surfaces come into engagement with the paper and while the compensating rolls are disposed through the compensating apertures.

Operation

As illustrated in Figures 6 and 7, the feed is nearing the end of the first phase; that is, the phase in which the compensating roll and the feeding rolls are all acting on the strips to advance the same. When the forms have been advanced to that point where the terminals of the tread portions on the feed rolls are reached, the outer feed rolls discontinue feed, and the second phase of the feeding operation begins. Obviously, at this point, the pressure of the feed rolls is released on the strips and only the compensating roll is effective. Thus, the spacing of the holes in the strips; that is, the length of the sales forms, may be varied within reasonable limits, which limits are determined by the diameter of the central or compensating disc.

The compensating roll will continue to feed the strips (this will be apparent from Figure 6) until the central apertures, as shown in Figure 8, move into position between the compensating rolls. The compensating apertures are then in substantial registry and are large enough to provide a certain amount of clearance extending rearwardly from the point of contact of the compensating rolls so that the paper can be fed forwardly in an aligning phase without forcing the strips between the compensating rolls.

As shown in Figure 8, these compensating rolls also serve to pre-align, as is well known in the art, so that if one or more of the forms is lagging, the first form to reach the compensating rolls, will stop when its particular aperture advances out of feeding contact with the compensating rolls, and the rolls will therefore continue to contact the lagging forms and advance them until all of the apertures register and the compensating rolls contact each other through the apertures, as illustrated.

At this point the feeding pins (Figure 9) are moving up under the strips and will slip across the back margins of the marginal apertures into the apertures for engagement with the front walls of the apertures. These marginal apertures lag slightly back of a line drawn between the centers of the feeding rolls, thus permitting entry of the pins without damage to the strips, such as would be the case if the apertures were too far advanced. Therefore, in this final phase of strip advance, the strips are completely aligned; that is to say, the apertures are aligned since the pins contact the forward walls of the apertures and advance the strips by direct contact with the forward edges of the apertures, thus pulling them all into aligned contact against the forward faces of the pins.

Having described my invention, I claim:

1. In an autographic register, a platen over which superimposed continuous strips of forms are adapted to be moved, sets of rolls engaging the strips therebetween, said strips including three apertures in each form thereof disposed across the forms, the central aperture being larger than the outer two, certain of said sets of feed rolls engaging the strips in alignment with the outer apertures, one roll of each of said last-named sets including a periphery having a tread portion extending part of the distance around the roll and a relieved portion, a pin carried by said latter roll, projecting radially from the roll and adapted to engage the apertures just prior to the engagement of the tread portion of the roll therewith, and a set of com-

pensating rolls located centrally of the machine, said rolls engaging the strips in alignment with the large central aperture, whereby after the feed rolls have advanced the strips a certain distance, the compensating roll continues to engage the strips and feeds them until the large central aperture is disposed between the compensating rolls and the rolls engage through the apertures for purposes of alignment.

2. In an autographic register, a platen over which continuous strips of sales forms are adapted to be fed, sets of feed rolls adapted to engage the continuous strips therebetween for feeding the strips, one roll of one of said sets of feed rolls having a continuous tread surface extending entirely around its periphery, said tread surface adapted to register with apertures in the strips for idle movement when the apertures are reached, and another set including a roll providing a tread surface of much shorter length than the tread surface of the first-named roll, said tread surface of said second-named roll being effective for causing the feed of the strips, and means associated with the second-named roll, engageable in apertures in the strips for starting the feed of the strips just prior to the time that the respective tread surfaces engage the strips.

3. In an autographic register, a platen over which continuous strips of sales forms are adapted to be fed, sets of feed rolls adapted to engage the continuous strips therebetween for feeding the strips, one roll of one of said sets of feed rolls having a continuous tread surface extending entirely around its periphery and another set including a roll providing a tread surface of much shorter length than the tread surface of the first-named roll, and means on said latter roll for starting the feed of the strips just prior to the time that its tread surface engages the strips.

4. In an autographic register, a platen over which continuous strips of sales forms are adapted to be fed, each of said sales forms including feeding and aligning apertures, one of said apertures being larger than the others and located centrally of the strips and the others located adjacent the side edges of the strips, feeding rolls between and by which said strips are adapted to be fed, that feed roll disposed in alignment with the central aperture having its tread portion extending entirely around its periphery, the other rolls having partial tread surfaces, and starting pins projecting radially from the said other rolls just ahead of said tread portions thereof, whereby the central roll will continue to feed the strips after the ends of the tread portions of the latter rolls are reached and until the central apertures of the strips are disposed between the compensating rolls and feeding contact ceases, whereupon the feed will be continued for an aligning period when said pins engage in the apertures.

5. In an autographic register, a platen over which superimposed continuous strips of sales forms are adapted to be fed, sets of rolls for feeding said strips therebetween, at least one of the rolls having a tread surface shorter than another of the rolls and of a length less than required to feed the shortest sales form completely, said strips including central apertures adapted to cause discontinuance of the feed of the strips when the latter roll having the longer tread is aligned with said aperture, and means on the roll having the short tread engageable with aper-

tures in the strip for aligning the forms in the final stage of strip feed.

6. In an autographic register, a platen over which continuous strips of sales forms are adapted to be fed, said sales forms including feeding and aligning apertures, one of said apertures being located centrally of the strips and the others located adjacent the side edges of the strips, feeding rolls between and by which said strips are adapted to be fed, that feed roll disposed for registry with the central aperture having its tread portion extending entirely around its periphery, the other rolls having shorter tread surfaces, and starting pins projecting radially from the said other rolls just in front of their tread portions, whereby the central roll will continue to feed the strips after the ends of the tread portions of said other rolls are reached until the central apertures of the strips are disposed between the rolls of the central set of

rolls and feeding contact ceases between the central set of rolls and the strips and whereupon the feed will be continued for an aligning period when the pins engage in the apertures.

5. 7. In an autographic register, a platen over which superimposed continuous strips of sales forms are adapted to be fed, sets of rolls for feeding said strips therebetween, one of said rolls constituting a compensating roll and providing 10 a tread surface adapted to feed the continuous strips of sales forms until the apertures therein are disposed adjacent the aforesaid tread surface, said sets of rolls providing means for engaging in apertures in the strips of sales forms for aligning the forms and advancing them to final position, and means for initially starting the feed of the paper, following the complete feed of a set of forms, for feeding the next succeeding set of forms.

HARRY J. WAECHTER.
